UNITED STATES PATENT OFFICE.

WILLIAM CUTTILL, OF GODLEY, AND SAM MARSHALL AND PERCY MARSHALL, OF HYDE, ENGLAND.

SPINNING MACHINERY.

1,095,458.

Specification of Letters Patent.

Patented May 5, 1914.

Application filed May 18, 1912. Serial No. 698,170.

To all whom it may concern:

Be it known that we, WILLIAM CUTTILL, a resident of Godley, SAM MARSHALL, a resident of Hyde, and PERCY MARSHALL, a resident of Hyde, all in England, have invented certain new and useful Improvements in and Relating to Spinning Machinery, of which the following is a specification.

This invention relates to improvements in the construction and arrangement of parts of ring spinning, winding, and like machinery of the type in which the rings carrying the travelers are so formed and mounted that they rotate and are driven to rotate in the same direction as the spindles with which they coöperate. The spindles are rotated in the usual manner and the rovings or other yarns or threads are delivered to them in the usual way. Vertical reciprocating motion is given to the spindles according to this invention in the manner and by the means hereinafter described for the purpose of effecting the proper winding and building up of the cop, the ring rail remaining stationary. Or the same method of and means for vertically reciprocating the ring rail may be adopted, the spindles only being rotated. Such a method of reciprocating the ring rail is intended to be included as an alternative by a description of the reciprocation of the spindles.

The accompanying drawings illustrate somewhat diagrammatically the arrangement of a single spindle, ring and traveler, for spinning and winding on the bare spindle and the application thereto of our improved devices for effecting the vertical reciprocation of the spindle, from which the operation of a number of rings and spindles placed in a row in the usual manner of a ring frame will be understood. The spindle is arranged to reciprocate vertically while the ring rail is stationary.

Figure 1 is a front view of the machine. Fig. 2 is a plan view of the cams employed. Fig. 3 is a view to a larger scale showing the ring in section. Fig. 4 is a view of a detail of the spindle driving device. Fig. 5 is a

face view of one of the cams. Fig. 6 shows different views of another of the cams. Fig. 50 7 shows the cams in end view. Figs. 8 and 9 illustrate a ratchet device for actuating certain of the cams.

Referring to Fig. 1, A indicates the usual front rollers which deliver the attenuated 55 roving to the traveler B which can be of any usual construction. This traveler engages with the top flange of the ring C, and this ring is driven around or rotated in the same direction as the spindle D to which 60 it is delivering yarn. In the example illustrated the ring C is rotated by being attached to the upper face of a wherve E which is properly mounted in bearings to rotate in the ring rail F. The wherve and 65 ring are driven by a cord G from a suitable tin roller.

The lower end of the spindle D is carried in a bearing on the vertically reciprocable frame H in such a manner that although the 70 spindle is free to rotate it must move up and down with such frame. This up and down movement of the spindle within its ring is the equivalent of the motion that is usually given to the ring rail and it has the same 75 object, to properly wind the yarn on the spindle. The cam for giving this movement is indicated at J and it gives the reciprocating vertical movement to the spindle carrying frame H through the medium of the 80 stirrup H¹ which surrounds the cam and engages with its lower surface through the intermediary of a movable ball H².

K K are weights to slightly overbalance the weight of the frame H. 85

The cam J makes one revolution for a winding layer and a return binding layer of yarn upon the spindle. It is shaped to give the proper varying traverses to the spindle during the building of the cop bottom and 90 the winding of the cop, and is preferably shaped to give a rapid upward movement to the spindle and a slower downward movement, so that the binding convolutions of 95 yarn are laid in the known manner on the cop from the nose to the base of the conical sur-

face being wound. The cam J while constantly rotating with its shaft J^1 is moved axially along it so that although the winding and building of the cop bottom commences while the smaller end of the cam is governing the spindle frame H, the larger end of the cam is governing the spindle frame when the cop is finished. This axial movement of the cam J throughout its length during the complete winding of a cop is effected by means of the face cam L secured to a shaft L^5 to which one complete rotation is given during the completion of a cop. The cop bottom is built while the spindle frame H is reciprocated by the conical part of the cam shown at its left hand end; the remainder of the cam reciprocates the spindle during the winding of the remainder of the cop. A long cam J may be used which is moved axially at a constant speed during the building of the cop bottom and the winding of the cop, but it is preferred to use a short cam and to give it varying speeds of axial traverse by giving a suitable contour to the face of the cam L.

L^1 is an arm for transmitting the motion of the cam L to the cam J. It is secured to and rocks with a vertical rock shaft L^2 , which also has a short arm L^3 carrying a friction bowl engaging with the cam L.

L^4 is a sliding support for the arm L^1 . The end of the arm L^1 is connected to the shaft L^2 by being hinged to a collar which rotates with the shaft but can slide along it.

In addition to constantly rotating, the shaft J^1 of the cam J is progressively lowered during the formation of a cop, being at its highest position at the commencement of the building of a cop bottom and at its lowest when the cop is finished. The spindle frame, through its engagement with the cam J, and consequently the spindles are thus gradually and correspondingly lowered during the building of a cop. This is effected by mounting the shaft J^1 in bearings which can slide up and down in brackets J^2 (in which the frame H also slides). The shaft J^1 is engaged by the front forked ends of two armed levers M, M, fulcrumed on a shaft M^1 . The rear ends of these levers engage by friction bowls with cams N. They and the cams are so disposed that at the commencement of the building of a cop bottom the bowls are at the greatest diameters 1 of the cam surfaces. (See Fig. 5.) The cam shaft J^1 is then in its highest position. The cams N rotate only once during the complete winding of a cop so that when the cop is complete the cam shaft J^1 is in its lowest position. The shaft carrying the cams N has a step by step angular motion given to it by a pawl and ratchet or the like, one step for each complete winding

and binding traverse of the spindle. This ratchet device is shown in Figs. 8 and 9. 65 The ratchet wheel S is keyed to the shaft L^5 on which is loosely mounted the bell crank lever T the upright arm of which carries the pawl U engaging with the teeth of the ratchet wheel and the horizontal arm of 70 which rests upon a cam V keyed to the shaft W driven at a suitable speed and advancing the shaft L^5 one step for each revolution of the cam V.

Details of an intermediate bearing support 75 for the spindle are shown in Fig. 4. Fixed on to a suitable rail P is a bearing Q in which the spindle properly rotates, and in which it can have longitudinal movement. Inclosed within the bearing is the wherwe 80 R, which engages by a feather key and key way or the like or by balanced keys and key ways with the spindle D. The spindle is thus compelled to rotate with the wherwe R but can freely slide up and down 85 within it. The wherwe R is driven in the usual way from a tin roller.

The rotating ring C rotates at a regular speed during the operation of the machine, and its speed may have any desired relation 90 to the speed of rotation of the spindle. As an example with a spindle rotation of 7000 a minute a ring rotation of 6000 may be employed.

As has before been explained the spindles 95 may only rotate, as is usual in ring frames, and the vertical reciprocating motion may be given to the rotating rings. This may be effected by mounting the rings in proper rotary bearings in a ring rail, the rings being provided with downwardly extending sleeves which key for rotation with but can slide within wherves attached to and rotating on a fixed rail. The ring rail is then reciprocated in the usual manner of the 105 present ring rails.

When the cop is completed and doffed the different parts are returned to their commencing positions as is usual in ring spinning machinery.

110

What we claim is:—

1. In a ring frame, rotary rings bearing the travelers, rotary and vertically reciprocable spindles, means for slightly overbalancing the weight of the same, a rotary and axially movable cam for controlling the reciprocations of the spindles, a second cam for effecting the axial movement of the first cam, and a third cam for effecting the progressive lowering of the spindles, substantially as hereinbefore set forth.

2. In a ring frame, rotary rings bearing the travelers, rotary and vertically reciprocable spindles, means for slightly overbalancing the weight of the same, a rotary and axially movable cam for controlling the re-

125

ciprocations of the spindles such cam being so formed as to lay the binding convolutions of yarns downward from the noses of the cops, a second cam for effecting the axial movement of the first cam, and a third cam for effecting the progressive lowering of the spindles, substantially as hereinbefore set forth.

In witness whereof we have hereunto set

our hands in the presence of two subscr- 10
ing witnesses.
